TIMBER-HANDLING DEVICE

Application filed March 7, 1928. Serial No. 259,713.

This invention relates to lifting devices for handling railroad ties, logs, beams, posts and other heavy timbers. The invention has been made more particularly with the idea of providing a device for the rapid and convenient loading and unloading or other moving about of railroad ties, but obviously the invention is not limited to such use.

In U. S. Patent No. 1,291,437, dated January 14, 1919, there is described and claimed a device adapted to be swung from a crane or derrick and having a plurality of pairs of gripping hooks, each connected to a supporting member by a chain or other suitable connecting means, the connecting chains for each pair of hooks being adapted to extend outward from opposite sides of the supporting member, so that the several pairs of hooks are adapted to grip the ends of a number of ties lying side by side, and so that when the supporting device is lifted the hooks of each pair will be drawn inward and caused to grip the ends of the tie to be lifted thereby.

The present invention aims especially to provide a device having, like that shown in said patent, a plurality of pairs of gripping hooks carried by connecting devices extending outward from opposite sides of a supporting member for gripping the ends of, and lifting a plurality of ties or other heavy pieces of timber laid side by side, which shall be so constructed as to be capable of readily lifting timbers differing very considerably in length, and which shall be provided with means whereby the gripping hooks, when placed in position against the ends of the timbers to be lifted, will be held in place by being drawn against the ends of the timbers until the main body or supporting member of the device is raised to cause the hooks to strongly grip the ends of the timbers and to lift them. To these ends, the device is provided with means whereby the connecting members which carry the hooks may be drawn outward to the extent necessary for placing the hooks of each pair in position at the ends of the timber to be lifted thereby, whatever the length of the timber within the capacity of the device, and whereby each such connecting member, after its hook has been

placed in position against the end of a timber will be pulled inward with sufficient force to hold the hook in position against the end of the timber until such time as the supporting member is lifted; and with means whereby when the supporting device is raised to lift the timbers gripped by the hooks, outward movement of the connecting members from the position in which their hooks are in engagement with the ends of the timbers will be prevented or limited, so that, as the supporting member is lifted, the hooks of each pair will be caused to grip the ends of the timber with which they have been placed in engagement. The locking means for holding the connecting members against outward movement from any position of adjustment in which their hooks are positioned against the ends of timbers to be lifted are most desirably arranged to come into operation automatically when the supporting member is raised.

While the invention aims especially to provide a lifting device for lifting a plurality of timbers at one time, features of the invention may be embodied in a device adapted for lifting only a single piece of timber at a time.

A full understanding of the invention can best be given by a detailed description of a lifting device embodying the various features of the invention in the form now considered best in connection with drawings illustrating such a device, and such a description will now be given in connection with the accompanying drawings, in which:

Fig. 1 is a top plan view of a lifting device according to the invention;

Fig. 2 is a side view;

Fig. 3 is a sectional view taken on line 3—3 of Fig. 1, showing the parts in position when the lifting cable is slack and its supporting member is resting on ties or other timbers to be lifted, and with one of the pairs of hooks shown placed in position against the ends of a timber; and

Fig. 4 is a sectional view taken on line 4—4 of Fig. 1, showing the parts in position at a time when the supporting member has been raised to lift a timber or timbers.

100

Referring to the drawings, the device as shown comprises a supporting member 10 which is most desirably, and as shown, a rectangular frame, conveniently formed of angle bars 11 and side bars 12 extending between end plates 13. The supporting member is adapted to be lifted by a cable 15 connected to a shackle 16 attached to an upper bar or beam 17 which extends longitudinally of the frame 10 and is connected at its ends to the end plates 13 by means of studs 18 extending into loops 19 which project upwardly from the end plates, these parts being proportioned so that by reason of movement of the pins 18 vertically within the loops 19 the bar 17 is permitted a limited vertical movement relatively to the supporting member. The purpose of this relative vertical movement permitted to the bar 17 will be explained later.

The supporting frame carries a plurality of pairs of winding drums, or spools, 20 and 21 mounted to turn on parallel shafts 22 and 23 the ends of which are fixed in the end plates 13. Connected to each of the drums 20 is a flexible connecting member 24 which is adapted to extend outward from the side of the frame and which carries at its outer end a gripping hook 25. Each of the drums 20 is provided with a coiled spring 26 which tends to turn the drum to wind the flexible connecting member thereon and draw its hook inward toward the side of the frame. Similarly, each of the drums 21 has connected to it a flexible connecting member 30 adapted to extend out from the other side of the frame and which carries a gripping hook 31, and for each of the drums 21 there is provided a coiled spring 32 which tends to turn the drum to wind its connecting member thereon and draw its hook 31 inward toward the side of the frame. The connecting members 24 and 30 are conveniently formed of chains but may be of any suitable flexible material. They extend from the drums out through openings in the side walls of the frame, as shown, through openings in the side bars 12 and the side bars thus form stops against which the hooks come home when not in use. By having the side bars 12 spaced somewhat away from the angle bars 11 an opening is provided into which the ends of the hooks may extend. The gripping hooks may be of any suitable form, but are most desirably double pronged hooks, as shown.

For preventing turning of the drums to permit outward movement of the connecting chains when the supporting device is being raised after the gripping hooks have been positioned at the ends of timbers to be lifted, each of the drums is provided with a ratchet wheel 40 or 41 secured to turn with the drum and adapted to be engaged by a pawl 42 or 43. The pawls 42 for the ratchet wheels 40 of the drums 20 are mounted on a shaft 44 extending between the end plates 13 above

the drum shaft 22, and the pawls 43 for holding the ratchet wheels 41 of the drums 21 are mounted on a similar shaft 45 extending between the end plates above the drum shaft 23. In order that the pawls 42 and 43 shall be held out of engagement with their ratchet wheels when the supporting frame is not being lifted, as, for example, when it is resting on a layer of timbers and the lifting cable is slack as shown in Fig. 3, each of the pawls is provided with an arm 46 which extends inwardly beneath the lifting beam 17, so that when the beam 17 is in its lower position relatively to the frame, as shown in Fig. 3, the arms 46 will be depressed and the pawls lifted out of engagement with their ratchet wheels. When, however, the lifting beam is raised by an upward pull of the lifting cable, the pawl arms 46 are released and the pawls drop into operative position to contact each with its ratchet wheel to lock the corresponding drum against turning in the direction to permit outward movement of its connecting member and hook.

In the use of the lifting device, the supporting frame 10 is placed crosswise on, and about midway of the length of, a layer or course of ties or other timbers to be lifted, and the lifting cable is slackened to permit the beam 17 to drop and depress the pawl arms 46 to release the ratchet wheels. The gripping hooks are then pulled outward and placed in position with their prongs lying over the ends of the timbers, the two hooks of each pair, that is, those carried by connecting devices extending from opposite drums 20 and 21, being positioned against the opposite ends of the same piece of timber. The winding drums are turned against the tension of their springs when the hooks and connecting chains are pulled outward, and when the hooks have been positioned against the ends of the timbers the springs tend to turn the drums to draw inward on the connecting members sufficiently to hold the hooks in position against the ends of the timbers. The hooks having been thus positioned, when the lifting cable draws upward on the beam 17 to raise the supporting frame, the beam 17 is first lifted relatively to the frame to release the pawls and permit them to drop into operative position to lock each of the drums against unwinding movement when it has turned sufficiently to bring a tooth of its ratchet wheel into engagement with its pawl. Then as the supporting frame is raised, a large component of the strain on the hooks will be in the direction inward longitudinally of the timbers so as to cause the points of the hooks to sink into and tightly grip the ends of the timbers, and, as the upward movement of the frame continues, the timbers are lifted and may then be shifted and lowered and deposited as desired. When the timbers are lowered and come to rest, further down-

ward movement of the frame causes a lessening in the strain on the connecting chains, and the hooks may be readily disconnected from the ends of the timbers; and when the 5 hooks are disconnected and released, the drums will be turned by their springs to draw the chains and hooks inward until the hooks come to rest against the side of the frame.

It will be seen that a device such as shown 10 may be used for lifting timbers of various lengths, the length of a timber which can be lifted depending upon the length of the connecting chains, the spacing of the pairs of drums, and the winding capacity of the 15 drums. It will be also be seen that timbers of different lengths may be lifted at the same time.

It is to be understood that the invention 20 is not to be limited to the exact construction shown and to which the foregoing description has been largely confined, but that it includes changes and modifications thereof within the claims.

What is claimed is:

25 1. A lifting device for articles such as railroad ties and other heavy timbers, comprising a supporting member, a pair of spring actuated winding drums carried by the supporting member, a pair of flexible connecting 30 members extending in opposite directions one from each drum, a gripping hook carried by each connecting member, and locking means for automatically locking the drums against unwinding movement when the supporting 35 member is raised.

2. A lifting device for articles such as railroad ties and other heavy timbers, comprising a supporting member, a pair of spring actuated winding drums carried by the supporting member, a pair of flexible connecting 40 members extending in opposite directions one from each drum, a gripping hook carried by each connecting member, and means movable into and out of operative position for 45 locking the drums against unwinding movement.

3. A lifting device for articles such as railroad ties and other heavy timbers, comprising a supporting member, a pair of spring actuated winding drums carried by the supporting member, a pair of flexible connecting 50 members extending in opposite directions one from each drum, a gripping hook carried by each connecting member, a lifting member having a limited vertical movement relatively to the supporting member and through which lifting effort is transmitted to the supporting member, and locking means for the drums controlled by the relative movement 55 of said lifting member to release the drums when the lifting member is down and to lock the drums against unwinding movement when the lifting member is up relatively to the supporting member.

65 4. A lifting device for articles such as rail-

road ties and other heavy timbers, comprising a supporting member, a pair of connecting members adapted to extend outward in opposite directions from the supporting member and to swing vertically, a gripping device 70 carried by each connecting member and formed to grip under strain of its connecting member, means tending to draw the connecting members inward but permitting them to be drawn outward for positioning the gripping devices against the ends of a timber 75 to be lifted, and means for holding the connecting members against outward movement.

5. A lifting device for articles such as railroad ties and other heavy timbers, comprising a supporting member, a pair of spring actuated winding drums carried by the supporting member, a pair of flexible connecting 80 members extending in opposite directions one from each drum, a gripping hook carried by each connecting member, and means for automatically locking the connecting members against outward movement when the supporting member is raised.

6. A lifting device for articles such as railroad ties and other heavy timbers, comprising a supporting member, a pair of gripping hooks connected to the supporting member to have a downward and inward movement relatively thereto and movable outward therefrom for positioning them against the ends of a timber to be lifted, means tending to draw the hooks inward to hold them in position against the ends of a timber before the supporting member is lifted, and locking 95 means for holding the hooks against outward movement when the supporting member is raised to lift the timber.

7. A lifting device for railroad ties and other heavy timbers, comprising a supporting member, a plurality of pairs of connecting members adapted to extend outward from the supporting member and to swing vertically, the connecting members of each pair extending outward in opposite directions, a gripping hook carried by each connecting member, means tending to draw the connecting members inward, and releasable locking means for holding the connecting members against outward movement.

8. A lifting device for railroad ties and other heavy timbers, comprising a supporting member, a plurality of pairs of connecting members adapted to extend outward from the supporting member and to swing vertically, the connecting members of each pair extending outward in opposite directions, a gripping hook carried by each connecting member, means tending to draw the connecting members inward, and locking means for automatically locking the connecting members against outward movement when the supporting member is raised.

9. A lifting device for railroad ties and other heavy timbers, comprising a support-

ing member, a plurality of pairs of connecting members adapted to extend outward from the supporting member and to swing vertically, the connecting members of each pair extending outward in opposite directions, a gripping hook carried by each connecting member, means tending to draw the connecting members inward, a lifting member through which lifting effort is transmitted to the supporting member and which has a limited movement relatively to the supporting member, and locking means controlled by the relative movement of said lifting member to release the connecting members when the lifting cable is slack and to lock the connecting members against outward movement when the supporting member is raised.

10. A lifting device for railroad ties and other heavy timbers, comprising a supporting member, a plurality of pairs of connecting members adapted to extend outward from the supporting member and to swing vertically, the connecting members of each pair extending outward in opposite directions, a gripping hook carried by each connecting member, and means for independently adjusting the effective length of each connecting member.

11. A lifting device for railroad ties and other heavy timbers, comprising a supporting member, a series of independently rotatable winding drums carried by the supporting member, a flexible connecting member secured to each drum and adapted to extend outward from one side of the supporting member, a second series of independently rotatable winding drums carried by the supporting member, a flexible connecting member secured to each drum of said second series and adapted to extend outward from the other side of the supporting member, a gripping hook carried by each connecting member, and means for locking the drums against unwinding movement from any position to which they have been individually turned.

12. A lifting device for railroad ties and other heavy timbers, comprising a supporting member, a series of independently rotatable winding drums carried by the supporting member, a flexible connecting member secured to each drum and adapted to extend outward from one side of the supporting member, a second series of independently rotatable winding drums carried by the supporting member, a flexible connecting member secured to each drum of said second series and adapted to extend outward from the other side of the supporting member, a gripping hook carried by each connecting member, a spring for each drum tending to turn the drum to wind its connecting member thereon, and locking means movable into and out of operable position for locking the drums against unwinding movement.

13. A lifting device for railroad ties and

other heavy timbers, comprising a supporting member, a series of independently rotatable winding drums carried by the supporting member, a flexible connecting member secured to each drum and adapted to extend outward from one side of the supporting member, a second series of independently rotatable winding drums carried by the supporting member, a flexible connecting member secured to each drum of said second series and adapted to extend outward from the other side of the supporting member, a gripping hook carried by each connecting member, and locking means for automatically locking the drums against unwinding movement when the supporting member is raised.

14. A lifting device for railroad ties and other heavy timbers, comprising a supporting member, a series of independently rotatable winding drums carried by the supporting member, a flexible connecting member secured to each drum and adapted to extend outward from one side of the supporting member, a second series of independently rotatable winding drums carried by the supporting member, a flexible connecting member secured to each drum of said second series and adapted to extend outward from the other side of the supporting member, a gripping hook carried by each connecting member, a ratchet wheel on each drum, a pawl for coacting with each ratchet wheel to lock its drum against unwinding movement, and a lifting beam through which lifting effort is transmitted to the supporting member and which is mounted to have a limited vertical movement relatively to the supporting member and is adapted to coact with said pawls to hold the pawls out of operative position when the beam is in its down position relatively to the supporting member and to release the pawls when the beam is raised relatively to the supporting member.

In testimony whereof, we have hereunto set our hands.

CHARLES E. DOTY.
OTTO G. DESCH.
